COOLER FOR ENGINES

August Gunnar Ferdinand Wallgren, Eskilstuna, Sweden, assignor to Aktiebolaget Bolinder-Munktell, Eskilstuna, Sweden, a corporation of Sweden

Application October 23, 1940, Serial No. 362,325
In Sweden November 18, 1939

1 Claim. (Cl. 257—259)

This invention refers to radiators for engines, more particularly internal combustion motors, in which the ultimate cooling medium consists of a liquid or of air. The radiator is intended to be used for the cooling of water circulating through the engines as well as of oil, for example.

One object of the invention is to provide a radiator having high values of heat transmission between the various media and the walls of the radiator, while the resistance to the flow of the media through the radiator and thus the sacrifice of energy in the functioning of the radiator is low. Another object of the invention is to provide a radiator which, while being of small dimensions, is capable of carrying off large quantities of heat from the medium heated by the motor, such as water or oil. Further objects of the invention are to provide a radiator which is of a stable and sturdy construction so as not to be damaged by the vibrations of the motor or by any external strains, and which from a manufacturing point of view shows great advantages by a rational and simple construction.

Further objects and advantages of the invention will be apparent from the following description considered in connection with the accompanying drawings which form a part of this specification, and of which:

Fig. 1 is a longitudinal section taken on the line I—I of Fig. 2 through a radiator constructed in accordance with the invention, said radiator operating with air as a cooling medium; and

Fig. 2 is a section taken on the line II—II of Fig. 1;

Figs. 3 and 4 show sections taken on the lines III—III and IV—IV of Fig. 2, respectively, on an enlarged scale.

In the embodiment according to Figs. 1—4, 10 designates a fan wheel having impeller blades 12, the hub 11 of which is preferably adapted to be arranged directly on the crank shaft of a motor. A ring of stationary guide blades 13 may be provided outside the fan wheel to impart the desired direction of flow to the air. The radiator proper is arranged radially outside the fan wheel 10 and the blade ring 13. The radiator consists of sheet metal plates 14 disposed in planes at right angles to the motor shaft and the fan shaft, respectively, said plates being in the present case distributed in a number of groups located about the outer periphery of the fan wheel. Each group comprises a suitable number of sheet metal plates forming a unit of a thickness corresponding approximately to the width of the fan wheel and of the guide blade ring, respectively. The plates are provided

at their opposite ends with ear-shaped projections, the projections at one end being diagonally disposed with relation to the projection at the other end. The projections adjacent to the radially outer edges of the plates are formed with openings or holes 15 while the projections adjacent to the radially inner edges have openings or holes 16 therethrough. As shown in Fig. 2, the units are preferably so arranged that the inner and outer projections of the plates overlap in peripheral direction, and hence the openings 15 and 16 in the adjacent ends of adjacent units are located on the same radial line from the centre of the fan wheel, the row of holes 16 being then innermost. The sheet metal units are arranged between two disks 17 and 18 which are preferably provided with openings 19 and 20, respectively, in alignment with the holes 15 and 16. The plates 14 are clamped between the disks 17 and 18 by means of bolts 21 passing through the holes 15 and 16 in the plates and the openings 19 and 20 in the disks. The liquid to be cooled, such as water or oil, enters through a pipe connection 22 to the two uppermost rows of holes 15, and escapes through another pipe connection 23 adjacent the two lowermost rows of holes 16. The two pipe connections may be provided diametrically opposite one another.

There are spaces between the sheet metal plates 30 of the various units, alternate spaces being traversed by the cooling air and intermediate spaces traversed by the hot liquid from the motor entering through the pipe connection 22. In order to separate the different fluid spaces from one another, the holes 15 and 16 are surrounded by one or more rings or washers 24 which also serve as distance pieces for the spaces 25 through which the air passes. These rings permit free passage of the air outwardly from the fan outlet. The spaces 40 26 between the plates intended for the liquid are laterally closed by frame-like packings 27 which have similar outer contours as the plates 14 and consequently also extend about the holes 15 and 16. The packing elements 24 and 27 may consist 45 of metal, and may be welded to the plates, for instance by seam or spot welding. Consequently the various paths of flow within the plate units are separated from each other in a fluid-tight fashion, and furthermore, the plate units attain a stable and sturdy shape. Packing members 30 may be inserted between two adjacent plate units, especially the two uppermost and lowermost units in Fig. 2, in order to prevent outward flow of the cooling air at these points.

55 The sheet metal plates 14 are corrugated and

the corrugations extend on both sides of the plane of the edge portion and have an extent beyond this plane of 2 mm., for example. Preferably, the corrugations of two plates forming an air passage are placed so that the passage is of substantially uniform thickness in the path of the cooling air, that is to say the corrugations of the two plates here extend in parallel relationship. On the other hand, the water spaces 26 are bounded by plates with the corrugations disposed in a crosswise fashion (see 40 in Fig. 2), which results in the spaces having a varying thickness. The corrugations of the various plates may extend at an inclination to planes through the centre of the radiator. Two sheet metal plates forming a space 15 10 26 may contact each other at points, as will be seen from Fig. 4.

The hot liquid entering through the conduit 22 flows in the embodiment illustrated into the rows of holes 15 pertaining to the two uppermost plate units in Fig. 2. From here, a portion of the liquid passes through the spaces 26 between the plates, where it is cooled by the transmission of heat through the plates to the air flowing through the spaces 25, and thence escapes through the rows of holes 16 to a circular channel 28, which may be formed by the disk 18 and an annular element 29 arranged outside the same. Another portion of the hot liquid continues straight through the said rows of holes 15 into an annular channel 39 which is preferably provided in the same manner as the channel 28. The hot liquid follows the channel 39 in both directions to the lower units and enters into the latter through the holes 15. Thereafter, the liquid, after having been cooled, escapes to the collecting channel 28 through the holes 16. The cooled liquid is led off through the two lowermost rows of holes 16 to the connection 23.

According to the invention, very high heat transmission is obtained between the air and the plates on the one hand, and between the liquid and the plates on the other hand. In both instances a well balanced turbulence of the heat-

exchanging media is ensured, and at the same time the resistance to flow is small. By reason of the low resistance in the air passages of the cooler, the fan will have to compress the air to a small extent only, for instance to a pressure corresponding to a water column of 10—20 mm. According to the invention, the requisite quantity of air may be obtained without the fan being geared up to rotate faster than the crank shaft, the fan being then preferably arranged directly on the shaft of the motor. The radiator in its entirety will be of small dimensions and have a small diameter. As the air is blown through the radiator, the turbulence is greater than when the air is sucked through the same.

Obviously, the invention is not limited to the embodiments above described, but may be varied in many respects without departing from the scope of the invention. In the embodiment shown the channels 28 and 29 may be separated, if desired, by a heat-insulating wall, or, they may be arranged each on one side of the cooler to counteract heat transmission between the same.

What I claim is:

In a radiator, a plurality of spaced sheet metal plates having flat edge portions extending peripherally therearound and undulated inner portions, said flat edge portions being formed with fluid distributing openings at spaced apart locations, packing frames between adjacent plates taken in pairs for forming fluid-tight chambers therebetween, packing rings between adjacent plates of adjacent pairs and in alignment with said openings for providing air spaces between said pairs and fluid connections between said chambers, said adjacent plates which bound opposite sides of the air spaces being arranged with their respective corrugations parallel and the plates of each pair which bound opposite sides of the fluid chamber being disposed with their respective corrugations in angular relation.

AUGUST GUNNAR
FERDINAND WALLGREN.
